WATER SAFETY FLOTATION DEVICE

David W. Bales, 122 Market, Washington, Mo. 63090

Filed Jan. 16, 1967, Ser. No. 5,430

Term of patent 3½ years

(Cl. D71—1)

FIG. 1 is a perspective view of a water safety flotation device embodying my new design;

FIG. 2 is an elevational view of the front or rear of same;

FIG. 3 is an elevation of either side thereof;

FIG. 4 is a top plan view, and

FIG. 5 is a bottom plan view thereof.

The dominant features of my design reside in the portions shown in full lines; the broken line showing of the attaching strap is fragmentarily shown for convenience of illustration.

I claim:

The ornamental design for a water safety flotation device, as shown and described.
